PRESSER HEAD UNIT FOR USE WITH A STEAM
REMOVAL ATTACHMENTMory Leven, New York, N.Y., assignor to Vap-O-Vac
Systems, Inc., New York, N.Y., a corporation of New
York

Filed June 29, 1966, Ser. No. 2,864

Term of patent 14 years

(Cl. D49—1)

FIG. 1 is a front elevational view of a presser head unit for use with a steam removal attachment embodying my new design;

FIG. 2 is a top plan view thereof;

FIG. 3 is a bottom plan view thereof showing the bottom which is open;

FIG. 4 is a rear elevational view thereof; and,

FIG. 5 is a side elevational view thereof, the opposite side being identical with the side shown.

I claim:

The ornamental design for a presser head unit for use with a steam removal attachment, as shown and described.
